UNITED STATES PATENT OFFICE.

JESSE B. FORSHAY, OF DENVER, COLORADO, ASSIGNOR OF ONE-HALF TO B. E. WELDY,
OF DENVER, COLORADO.

MANIFOLD HEATER.

Application filed November 28, 1923. Serial No. 677,583.

This invention aims to provide novel means whereby the fuel proceeding to an internal combustion engine may be heated to any desired degree, within the intake manifold at the will of an operator, the advantages incident to heating the fuel before it is delivered into the cylinders being well understood.

In the drawings:—Figure 1 shows in side elevation, a device constructed in accordance with the invention, applied to an internal combustion engine, parts being broken away; Figure 2 is a cross section on the line 2—2 of Figure 1; Figure 3 is a cross section taken through the manifold in Figure 1; Figures 4 and 5 are cross sections showing modifications; and Figure 6 is a plan showing a portion of the structure used in Figure 1, parts being broken away.

In the accompanying drawings, numeral 1 indicates the exhaust manifold of an internal combustion engine, the intake manifold being marked by the numeral 2 and the dash board being designated by the numeral 3. A conduit 4 extends through the intake manifold 2, longitudinally thereof, the conduit carrying, beyond the manifold 2, a muffler 18. At one end, the pipe or conduit 4 communicates with a valve casing 5, connected by a pipe 6 with one end of the exhaust manifold 1, a union being interposed in the pipe 6.

A valve 7 is mounted in the valve casing 5 and has a depending stem 8 provided with a laterally extended arm 9, loosely connected by means of a link 10 with an arm 11 on an inclined shaft 12 journaled in a bearing 14 carried by a bracket 15 mounted on the intake manifold 2, the shaft 12 being journaled likewise, in the dash board 3, and there being a dial 16 on the dash board, the shaft carrying a combined handle and indicator 17 adapted to cooperate with the dial.

That part of the conduit which is located within the manifold 2 is made up of two pipes 25, in contact with each other, so as to form a longitudinal recess 26.

In practical operation, the shaft 12 may be rotated to any desired extent, through the

instrumentality of the handle 17, the handle cooperating with the dial 16 to denote the amount that the shaft 12 has been rotated. When the shaft 12 has rotated, the arm 9 on the shaft coacting with the link 10, imparts rotation to the valve 7 through the instrumentality of the arm 9 and the stem 8, the valve being opened more or less, so that a greater or less part of the exhaust product from the manifold 1 may move through the pipe 6 and the pipe 4, the fuel, as it passes through the intake manifold 2, being heated by coming into contact with that portion of the pipe or conduit 4 which is located within the intake manifold. The muffler 18 causes the device to operate without any increase noise.

In Figure 4, the intake manifold is marked by the numeral 27 and the neck appears at 28. The conduit is made up of three pipes 29, 70 disposed in triangular form, to form the longitudinal recess 30.

In Figure 5 of the drawings, the intake manifold is shown at 31, and the neck appears at 32. The conduit in this instance, is 75 made up of four pipes 33, disposed into upwardly converging lines, thereby forming a longitudinal recess 34.

Owing to the fact that the recesses 26, 30, and 34, are provided, the fuel is caused so to spread laterally, and to move upwardly, as shown by the arrows in Figs. 3, 4, and 5, a peculiarly efficient structure resulting, and the fuel being heated to a maximum extent.

Having thus described the invention, what I claim is:—

The combination with the intake and exhaust manifolds of an internal combustion engine, of a conduit branched off from the exhaust manifold and extended through the intake manifold, the conduit being made up of a plurality of separate pipes so grouped with respect to each other, transversely, as to form, within the intake manifold, a recess in the bottom of the conduit, the walls of the recess diverging downwardly and laterally.

In testimony that I claim the foregoing as my own, I have hereto affixed my signature.

JESSE B. FORSHAY.
